(57) **CLAIM**

The ornamental design for a display screen or portion thereof with animated graphical user interface, as shown and described.

DESCRIPTION

FIG. 1 is a front view of a display screen or portion thereof with animated graphical user interface showing an image in the sequence showing our new design;

FIG. 2 is another image thereof;

FIG. 3 is another image thereof; and,

FIG. 4 is another image thereof.

The broken lines around the Figures show a display screen or portion thereof, and form no part of the claimed design. The broken lines within the Figures show portions of the animated graphical user interface that form no part of the claimed design.

The appearance of the animated images transitions between the images shown in FIGS. 1-4. The process or period in which one image transitions to another forms no part of the claimed design.
